Primary Examiner — Marissa J. Cash*Assistant Examiner* — William B Melliar(74) *Attorney, Agent, or Firm* — Knobbe, Martens, Olson & Bear, LLP(57) **CLAIM**

The ornamental design for a quadcopter as shown and described.

DESCRIPTION

FIG. 1 is a back, top, and left side perspective view of a quadcopter embodying my new design.

FIG. 2 is a front view thereof.

FIG. 3 is a back view thereof.

FIG. 4 is a left side view thereof.

FIG. 5 is a right side view thereof.

FIG. 6 is a top view thereof; and,

FIG. 7 is a bottom view thereof.

Broken lines are used to illustrate features of the quadcopter which form no part of the claimed design.
